Isaac N. Ross
By his atty, R. D. Smith

United States Patent Office.

ISAAC N. ROSS, OF HOLDEN, MASSACHUSETTS, ASSIGNOR TO
EARLE STOVE COMPANY.

Design No. 3,550, dated June 15, 1869.

DESIGN FOR A STOVE.

The Schedule referred to in these Letters Patent and making part of the same.

To all whom it may concern:

Be it known that I, ISAAC N. ROSS, of Holden, in the county of Worcester, and State of Massachusetts, have invented a new Design for Stoves; and I do hereby declare the following to be a full, clear, and exact description of the same, reference being had to the accompanying drawings, in which the figure represents, in perspective, a parlor-heater, for burning wood, with its castings and ornamentation according to the design herein claimed.

This stove is oval in horizontal section, with a top and base of cast-iron, in form and configuration, and with ornaments embossed thereon, as shown.

Upon the centre of the top is an open-work ornamental screen, to cover an opening in said top.

Upon the front side, midway between the base and top, is a vase, embossed in *alto-relievo*.

At the end is the door for the introduction of fuel, surrounded by an ornamental flange, by means of which the door-frame is secured to the body of the stove.

Near the base are two or more draught-registers, with ornamental, scalloped flanges; and the stove is supported upon feet having the form and configuration shown.

What I claim as my invention, is—

The design for stove-castings, as herein set forth.

Witnesses:

CHARLES WOOD,
SIDNEY SMITH.

ISAAC N. ROSS.
